ABSTRACT OF THE DISCLOSURE

There are prepared compounds having a formula selected from the group consisting of

(a)

(b)

where R₁, R₂, R₃, R₄, R₅ and R₆ are selected from the group consisting of hydrogen, hydrocarbyl, haloaryl, metal, ammonium and hydrocarbyl tin.

This invention relates to novel polyphosphonic acid salts and esters thereof.

The present application is a continuation-in-part of application Ser. No. 485,624, filed on Sept. 7, 1965, entitled Methane Diphosphonic Acid.

It is an object of the present invention to prepare novel polyphosphonic acids.

Another object is to prepare salts of such acids.

A further object is to prepare novel esters of such acids.

Still further objects and the entire scope of applicability of the present invention will become apparent from the detailed description given hereinafter; it should be understood, however, that the detailed description and specific examples, while indicating preferred embodiments of the invention, are given by way of illustration only, since various changes and modifications within the spirit and scope of the invention will become apparent to those skilled in the art from this detailed description.

It has now been found that these objects can be obtained by preparing compounds having one of the formulae

II

2

III

5

10

where R₁, R₂, R₃, R₄, R₅ and R₆ are the same or different and are selected from the group consisting of hydrogen, metal, ammonium, hydrocarbyl, e.g. alkyl and aryl, haloaryl or hydrocarbyl tin.

The esters of Formula I are conveniently prepared by reacting 1 mole of benzal chloride with 2 moles of dialkyl phosphite, a diaryl phosphite or a di(haloaryl) phosphite. The esters of Formula II are prepared in a similar fashion by replacing the benzal chloride with benzo trichloride.

The free acids of Formulae I and II can be readily prepared by hydrolyzing the esters of the same formula. Preferably the lower alkyl esters are used for such hydrolysis. The hydrolysis is preferably carried out with the aid of an acid catalyst, e.g. hydrochloric acid, sulfuric acid or the like.

The salts of Formulae I and II can be prepared quite readily by placing an aqueous or organic solution of a salt of the appropriate metal in contact with the free acid of Formulae I and II or with an alkali metal salt thereof.

As the starting secondary phosphites there can be used dimethyl phosphite, diethyl phosphite, dipropyl phosphite, dibutyl phosphite, di isobutyl phosphite, di tertiary butyl phosphite, di secondary butyl phosphite, diethyl phosphite, dihexyl phosphite, dicyclohexyl phosphite, dioctyl phosphite, diisodecyl phosphite, di decyl phosphite, dioctadecyl phosphite, diphenyl phosphite, di p-cresyl phosphite, di (p-nonylphenyl) phosphite, di (o-dodecylphenyl) phosphite, di (m-octylphenyl) phosphite, di (p-chlorophenyl) phosphite, di (2,4,5-trichlorophenyl) phosphite, di (2,4,5-tribromophenyl) phosphite, di benzyl phosphite.

Examples of compounds within the present invention are phenyl methane diphosphonic acid, phenyl methane triphosphonic acid, tetramethyl phenyl methane diphosphonate, tetraethyl phenyl methane diphosphonate, tetrapropyl phenyl methane diphosphonate, tetrabutyl phenyl methane diphosphonate, tetrahexyl phenyl methane diphosphonate, tetraoctyl phenyl methane diphosphonate, tetra isodecyl phenyl methane diphosphonate, tetra octadecyl phenyl methane diphosphonate, tetraphenyl phenyl methane diphosphonate, tetra (m-cresyl) phenyl methane diphosphonate, tetra (p-butylphenyl) phenyl methane diphosphonate, tetra (p-nonylphenyl) phenyl methane diphosphonate, tetra (p-dodecylphenyl) phenyl methane diphosphonate, tetra benzyl phenyl methane diphosphonate, tetra (p-chlorophenyl) phenyl methane diphosphonate, tetra (2,4,6-trichlorophenyl) phenyl methane diphosphonate, tetra (2,4,5-tribromophenyl) phenyl methane diphosphonate, hexamethyl phenyl methane triphosphonate, hexaethyl phenyl methane triphosphonate, hexaisopropyl phenyl methane triphosphonate, hexabutyl phenyl methane triphosphonate, hexa secondary butyl phenyl methane triphosphonate, hexa tertiary butyl phenyl methane triphosphonate, hexa amyl phenyl methane triphosphonate, hexa hexyl phenyl methane triphosphonate, hexa heptyl phenyl methane triphosphonate, hexa octyl phenyl

II

methane triphosphonate, hexa (decyl) phenyl methane triphosphonate, hexa (isodecyl) phenyl methane triphosphonate, hexa propyl phenyl methane triphosphonate, hexa phenyl phenyl methane triphosphonate, di octyl tetra phenyl phenyl methane triphosphonate, hexa (p-cresyl) phenyl methane triphosphonate, hexa (o-butyl-phenyl) phenyl methane triphosphonate, hexa (p-nonyl-phenyl) phenyl methane triphosphonate, hexa (p-tetradecylphenyl) phenyl methane triphosphonate, hexa (cyclohexyl) phenyl methane triphosphonate, hexa benzyl phenyl methane triphosphonate, hexa (p-chlorophenyl) phenyl methane triphosphonate, hexa (2,4,6-trichlorophenyl) phenyl methane triphosphonate, hexa (2,4,6-tribromophenyl) phenyl methane triphosphonate.

There are also included within the invention salts of the novel acids. These salts can be made from any of the metals in the periodic system. Thus there can be prepared alkali metal salts such as lithium, sodium, potassium, rubidium and cesium salts, alkaline earth metal salts such as calcium, barium strontium and magnesium, as well as salts of the metals such as zinc, cadmium, mercury, copper, silver, gold, titanium, zirconium, tin, chromium, tungsten, molybdenum, radium, manganese, iron, cobalt, nickel, platinum, palladium, uranium and the rare earths, e.g., hafnium and cerium. Ammonium salts can also be prepared. With the exception of the alkali metals and ammonium the salts that are formed are of the chelate type.

Alkyltin and aryltin salts (e.g., mono, di or trialkyltin salts) can also be made.

Illustrative examples of salts are sodium phenyl methane diphosphonate, potassium phenyl methane diphosphonate, rubidium phenyl methane diphosphonate, ammonium phenyl methane diphosphonate, calcium phenyl methane diphosphonate, barium phenyl methane diphosphonate, magnesium phenyl methane diphosphonate, beryllium phenyl methane diphosphonate, zinc phenyl methane diphosphonate, cadmium phenyl methane diphosphonate, mercury phenyl methane diphosphonate, cupric phenyl methane diphosphonate, silver phenyl methane diphosphonate, auric phenyl methane diphosphonate, titanium phenyl methane diphosphonate, zirconium phenyl methane diphosphonate, stannous phenyl methane diphosphonate, stannic phenyl methane diphosphonate, chromic phenyl methane diphosphonate, tungsten phenyl methane diphosphonate, molybdenum phenyl methane diphosphonate, manganese phenyl methane diphosphonate, ferrous phenyl methane diphosphonate, ferric phenyl methane diphosphonate, cobaltic phenyl methane diphosphonate, nickelous phenyl methane diphosphonate, platinum phenyl methane diphosphonate, palladium phenyl methane diphosphonate, uranium phenyl methane diphosphonate, uranyl phenyl methane diphosphonate, plumbous phenyl methane diphosphonate, hafnium phenyl methane diphosphonate, cerium phenyl methane diphosphonate, dibutyltin phenyl methane diphosphonate, monobutyltin phenyl methane diphosphonate, tributyltin phenyl methane diphosphonate, dioctyltin phenyl methane diphosphonate, diphenyltin phenyl methane diphosphonate, sodium phenyl methane triphosphonate, potassium phenyl methane triphosphonate, ammonium phenyl methane triphosphonate, rubidium phenyl methane triphosphonate, cesium phenyl methane triphosphonate, lithium phenyl methane triphosphonate, calcium phenyl methane triphosphonate, magnesium phenyl methane triphosphonate, beryllium phenyl methane triphosphonate, strontium phenyl methane triphosphonate, barium phenyl methane triphosphonate, radium phenyl methane triphosphonate, zinc phenyl methane triphosphonate, cadmium phenyl methane triphosphonate, mercury phenyl methane triphosphonate, cupric phenyl methane triphosphonate, silver phenyl methane triphosphonate, aurous phenyl methane triphosphonate, titanic phenyl methane triphosphonate, zirconium phenyl methane triphosphonate, plumbous phenyl methane tri-

phosphonate, stannous phenyl methane triphosphonate, stannic phenyl methane triphosphonate, chromic phenyl methane triphosphonate, tungsten phenyl methane triphosphonate, molybdenum phenyl methane triphosphonate, manganese phenyl methane triphosphonate, ferrous phenyl methane triphosphonate, ferric phenyl methane triphosphonate, cobaltic phenyl methane triphosphonate, nickelous phenyl methane triphosphonate, platinum phenyl methane triphosphonate, palladium phenyl methane triphosphonate, uranyl phenyl methane triphosphonate, cerium phenyl methane triphosphonate, hafnium phenyl methane triphosphonate, dibutyltin phenyl methane triphosphonate, dioctyltin phenyl methane triphosphonate, amylytin phenyl methane triphosphonate, triethyltin phenyl methane triphosphonate, di (o-tolyl) tin phenyl methane triphosphonate.

The esters coming within Formulae I and II supra are all useful as stabilizers for halogen containing vinyl and vinylidene resins, e.g. vinylchloride resins and as stabilizers for monoolefin polymers, e.g. polyethylene, polypropylene and ethylene-propylene copolymer. For such stabilizer uses there is normally employed 0.1-10 parts of the phosphorous containing ester per 100 parts of the polymer. The esters are also useful in preparing the free acids within Formulae I and II.

The free acids of Formulae I and II are all useful as curing agents for melamine-formaldehyde and urea-formaldehyde resins. They are also valuable for forming their metal salts and as detergent additives, extractants, sequestering agents, metal complexing agents, corrosion inhibitors, chelating agents, stabilizers and the like. The alkali metal and ammonium salts are particularly valuable in detergent compositions as additives and builders. They are superior in such compositions to sodium tripolyphosphate. The free acids and alkali metal and ammonium salts are extremely valuable because of their ability to act as sequestering agents to hold polyvalent metal compounds in aqueous solution. They also are useful to prevent the hydrolysis of alkali metal polyphosphates.

The metal salts (other than the alkali metal salts) are useful in providing a means for isolating the metals in a form in which they can be readily recovered. They are also useful as a soluble source of the metals. The hydrocarbyltin salts are useful as stabilizers for halogen containing resins, e.g. vinyl chloride resins.

The phenyl methane diphosphonic acid, phenyl methane triphosphonic acid and their alkali metal salts exhibit very low surface tension and are superior agents for metal extraction e.g. extraction of gold, silver, vanadium, molybdenum, copper, nickel and iron.

Unless otherwise indicated, all proportions are by weight.

Since the novel acids of the present invention have four or six acidic hydrogen atoms (Formulae I and II) in making the salts one or more of the acidic hydrogen atoms can be replaced by the metal or ammonium in forming the salts. Usually all of the acidic hydrogen atoms are replaced in making the salt and unless otherwise indicated when reference is made to a salt in the present specification all of the acidic hydrogen atoms are replaced. However, it should be understood that this is not an essential part of the present invention and the invention includes the partial as well as the complete salts, e.g. mono sodium phenyl methane triphosphonate, di sodium phenyl methane triphosphonate, tri sodium phenyl methane triphosphonate, tetra sodium phenyl methane triphosphonate, penta sodium phenyl methane triphosphonate, hexa sodium phenyl methane triphosphonate, di potassium phenyl methane triphosphonate, tetra potassium phenyl methane triphosphonate, hexa potassium phenyl methane triphosphonate, mono ammonium phenyl methane triphosphonate, tri ammonium phenyl methane triphosphonate, hexa ammonium phenyl methane triphosphonate, mono sodium phenyl methane tri-

diphosphonate, di sodium phenyl methane diphosphonate, tri sodium phenyl methane diphosphonate, tetra sodium phenyl methane diphosphonate, mono potassium phenyl methane diphosphonate, tetra potassium phenyl methane diphosphonate, di ammonium phenyl methane diphosphonate, tetra ammonium phenyl methane diphosphonate.

The compounds of the present invention, and in particular the esters are useful as plasticizers.

The compounds of the present invention, particularly the free acids, alkali metal and ammonium salts, are useful as stabilizers for alkyl phenols, e.g. nonyl phenol, octyl phenol, dodecyl phenol to prevent discoloration. All of the compounds of the present invention are useful as flame proofing agents in making polyurethanes. The free acids are useful as catalysts in polymerizing formaldehyde to make materials such as Delrin or Celcon.

Example 1

There were charged into the reaction vessel 23.0 grams (1.0 mole) of sodium metal along with 90 cc. of xylene and 80 cc. of tetrahydrofuran. The vessel was placed under a nitrogen blanket and 138.10 grams (1.0 mole) of diethyl phosphite added over a 35 minute period. An exothermic reaction ensued which was maintained at 62° C. by external cooling. After addition was complete the mixture was heated to 100° C. and held there until all of the sodium metal was gone. The mixture was cooled to 60° to 70° C. and 80.5 grams (0.5 mole) of benzal chloride were added gradually over a 25 minute period. An exothermic reaction ensued which was maintained at 60° to 70° C. by external cooling. The mixture was then heated for 4 hours at 70° to 75° C., cooled to 60° C. The liquid material was separated from the solid and the solid boiled 8 times with 100 cc. of benzene to extract the organic material. The eluate product was then distilled, terminal conditions being a pot temperature of 201° C., distillate temperature 125° C. and pressure 6 mm. The solid residue of 70 grams was tetraethyl phenyl methane diphosphonate.

Example 2

0.9 mole of tetra ethyl phenyl methane diphosphonate was refluxed with 5.4 moles of concentrated hydrochloric acid for 24 hours. Excess acid was removed by stripping under vacuum. 200 ml. of water were added and removed in vacuo, then finally 200 ml. of benzene were added and the water removed and separated by means of a Dean and Stark trap and the benzene was distilled over under reduced pressure yielding phenyl methane diphosphonic acid.

Example 3

There were mixed together 23.0 grams (1.0 mole) of sodium metal along with 90 cc. of xylene and 80 cc. of tetrahydrofuran and the mixture placed under a nitrogen atmosphere. There were then added over a 35 minute period 138.10 grams (1.0 mole) of diethyl phosphite using external cooling to control the reaction exotherm and maintain the temperature at 60 to 65° C. After addition was complete the mixture was heated to 100° C. and maintained there for about 1 hour until there was no more sodium. The mixture was cooled to 60° C. and there was started the addition of 64.5 grams (0.33 mole) of benzotrichloride (α, α, α -trichlorotoluene). The exothermic reaction was cooled to maintain the temperature at 60° to 65° C. during the 25 minute addition period. The mixture was heated at 70° to 75° C. for 7 hours and the sodium chloride filtered off. The product in the pot was then subjected to distillation, terminal conditions being a pot temperature of 205° C., distillate temperature 125° C. and pressure 4 mm. The solid residue in the pot was hexaethyl phenyl methane triphosphonate. This product was hydrolyzed and the hydrolysis product purified as in Example 2 to obtain phenyl methane triphosphonic acid.

Example 4

The procedure of Example 1 was repeated replacing the diethyl phosphite by an equimolar amount of dimethyl phosphite to obtain as the product tetramethyl phenyl methane diphosphonate.

Example 5

The procedure of Example 1 was repeated replacing the diethyl phosphite by an equimolar amount of dibutyl phosphite to obtain as the product tetrabutyl phenyl methane diphosphonate.

Example 6

The procedure of Example 1 was repeated replacing the diethyl phosphite by an equimolar amount of diisodecyl phosphite to obtain as the product tetraisodecyl phenyl methane diphosphonate.

Example 7

The procedure of Example 1 was repeated replacing the diethyl phosphite by an equimolar amount of diphenyl phosphite to obtain as the product tetraphenyl phenyl methane diphosphonate.

Example 8

The procedure of Example 3 was repeated replacing the diethyl phosphite by an equimolar amount of dimethyl phosphite to obtain as a product hexamethyl phenyl methane triphosphonate.

Example 9

The procedure of Example 3 was repeated replacing the diethyl phosphite by an equimolar amount of dibutyl phosphite to obtain as a product hexabutyl phenyl methane triphosphonate.

Example 10

The procedure of Example 3 was repeated replacing the diethyl phosphite by an equimolar amount of dioctyl phosphite to obtain as a product hexaoctyl phenyl methane triphosphonate.

Example 11

The procedure of Example 3 was repeated replacing the diethyl phosphite by an equimolar amount of diphenyl phosphite to obtain as a product hexaphenyl phenyl methane triphosphonate.

Example 12

The procedure of Example 3 was repeated replacing the diethyl phosphite by an equimolar amount of di(dodecyl) phosphite to obtain as a product hexa(dodecyl) phenyl methane triphosphonate.

Example 13

The procedure of Example 3 was repeated replacing the diethyl phosphite by an equimolar amount of di(p-tolyl) phosphite to obtain as a product hexa(p-tolyl) phenyl methane triphosphonate.

Example 14

To 1 mole of phenyl methane diphosphonic acid there were added 4 moles of 10% aqueous sodium hydroxide and the mixture was evaporated to dryness to produce tetrasodium phenyl methane diphosphonate.

Example 15

To 1 mole of phenyl methane triphosphonic acid there were added 6 moles of 10% aqueous sodium hydroxide and the mixture was evaporated to dryness to produce hexasodium phenyl methane triphosphonate.

7
Example 16

1 mole of phenyl methane triphosphonic acid was dissolved in 6 moles of 10% aqueous ammonium hydroxide to produce hexa ammonium phenyl methane triphosphonate, in solution. The salt was recovered by evaporating to dryness. 5

Example 17

1 mole of phenyl methane triphosphonic acid was dissolved in 4 moles of 10% aqueous sodium hydroxide and the mixture evaporated to yield tetra sodium phenyl methane triphosphonate. 10

Example 18

An aqueous lead acetate solution was mixed with an aqueous solution of hexasodium phenyl methane triphosphonate to form the chelated lead phenyl methane triphosphonate.

In similar fashion an aqueous ferric chloride solution was mixed with an aqueous solution of hexa potassium phenyl methane triphosphonate to form the chelated ferric phenyl methane triphosphonate.

Example 19

The procedure of Example 1 was repeated replacing the diethyl phosphite with an equimolar amount of di (2,4,6-trichlorophenyl) phosphite to obtain as the product tetra (2,4,6-trichlorophenyl) phenyl methane diphosphonate. 30

Example 20

The procedure of Example 3 was repeated replacing the diethyl phosphite with an equimolar amount of di (2,4,6-trichlorophenyl) phosphite to obtain as the product hexa (2,4,6-trichlorophenyl) phenyl methane triphosphonate. 35

I claim:

1. A compound having the formula

10 where R_1 , R_2 , R_3 , R_4 , R_5 and R_6 are selected from the group consisting of hydrogen, alkyl, phenyl, alkylphenyl, chlorophenyl, bromophenyl, benzyl, metal and ammonium.

15 2. A compound according to claim 1 wherein R_1 , R_2 , R_3 , R_4 , R_5 and R_6 are selected from the group consisting of alkyl up to 18 carbon atoms, phenyl, alkylphenyl up to 12 carbon atoms, chlorophenyl, bromophenyl and benzyl.

20 3. A compound according to claim 1 which is phenyl methane triphosphonic acid.

4. A compound according to claim 1 which is a salt.

5. A compound according to claim 1 which is an alkali metal salt of phenyl methane triphosphonic acid.

25 6. A compound according to claim 1 which is a hexa alkyl up to 18 carbon atoms phenyl methane triphosphonate.

7. Hexa phenyl phenyl methane triphosphonate.
